(57) **CLAIM**

The ornamental design for a rod lamp as shown and described.

DESCRIPTION

1. Rod lamp

FIG. 1.1 is a front, bottom perspective view of a rod lamp embodying our new design;

FIG. 1.2 is a front elevation view thereof;

FIG. 1.3 is a rear elevation view thereof;

FIG. 1.4 is an enlarged left side elevation view thereof;

FIG. 1.5 is an enlarged right side elevation view thereof;

FIG. 1.6 is a top plan view thereof; and

FIG. 1.7 is a bottom plan view thereof.

This rod lamp is used for filling and lighting in photography. The broken lines in the drawings illustrate portions of the rod lamp that form no part of the claimed design.
